By his attorney Charles G. Hendley

UNITED STATES PATENT OFFICE.

SAMUEL COHN, OF NEW YORK, N. Y.

AUTOMOBILE-SIGNAL.

1,292,709.

Specification of Letters Patent. Patented Jan. 28, 1919.

Application filed June 25, 1917. Serial No. 176,700.

To all whom it may concern:

Be it known that I, SAMUEL COHN, a citizen of the United States, and a resident of the borough of the Bronx, city and State of New York; have invented certain new and useful Improvements in Automobile-Signals, of which the following is a specification.

My invention relates to signals of the semaphore type by which a driver of an automobile may signal to drivers of cars behind or to a traffic officer ahead, or to both, so that such persons will be advised as to the intention of the driver of the automobile having the signal device.

The principal object of my invention is to provide a very simple and inexpensive device of this kind, one which can be sold almost as cheaply as the ordinary mirror attachment used on the front of automobiles. Another object of my invention is to simplify the construction of signal devices of this kind and to reduce the number of parts to a minimum, so that the device will not easily get out of order no matter how carelessly it is used and even when it is exposed to the weather.

In the drawing forming part of this application,

Figure 1 is a perspective view of my invention as applied to the windshield frame of an automobile,

Fig. 2 is a perspective view of the device on a larger scale,

Fig. 3 is an elevation of the device with one side of the casing removed to show the interior parts,

Fig. 4 is a rear elevation of the device, showing one of the signal plates raised.

Fig. 5 is a sectional view taken on the line 5—5 of Fig. 4,

Fig. 6 is a sectional view taken on the line 6—6 of Fig. 8,

Fig. 7 is a sectional view taken on the line 7—7 of Fig. 8,

Fig. 8 is a sectional view taken on the line 8—8 of Fig. 7.

Fig. 9 is a perspective view of one corner of the casing showing the means for detachably securing the mirror after it has been inserted in place,

Fig. 10 is an elevation of one of the mirror retaining members.

The device comprises a casing, semaphores or signals within the casing and adapted to be projected beyond the same, and of means for operating the signals.

The casing 1 shown herein comprises flat front and rear walls 2, 3, a top 4, a bottom 5 and one end wall 6, the opposite end 7 being open to allow the signals to move into and out of the casing. The casing is preferably attached to the windshield frame 8 by means of a bracket 9 which latter may be cast integral with the casing or it may be formed separately of the casing.

At the upper portion of the casing 1, there is a transverse arbor 10 forming a support on which the several signal plates 11, 12, 13 may swing and in the drawings I have shown three signal plates arranged side by side on this arbor 10. There may be a lesser or greater number of such signals, but with three marked, respectively, "Stop", "Right" and "Left" all the desired signals may be given to the drivers of other automobiles and to traffic officers.

When in the retracted position the several signal plates 11, 12, 13 hang down in parallel relation from their supporting arbor 10 and just within the open end of the casing, as is shown in full lines in Fig. 3. To the signal plate 11 there is fulcrumed at 14 a curved rod 15 which bends at 16 and from there it extends straight down and through a slot 17 in the bottom wall 5 of the casing. Where the rod 15 projects through the casing it is provided with an operating handle or knob 18. There is a rod 19 fulcrumed to the signal plate 12 in the same manner that the rod 15 connects with the plate 11 and the rod 19 bends outwardly at 20 far enough so that the vertical portion, which projects through a slot in the bottom wall 5, lies to one side of the vertical portion of the rod 15. The rod 19 has a knob 21 on its lower end. There is a rod 22 fulcrumed to the signal plate 13 and it bends outwardly at 23 so that its vertical portion lies beyond both the rods 15 and 19. Otherwise the rod 22 is the same as the rods 15, 19 and it passes through a slot in the bottom wall and is provided with a knob 24.

The above arrangement is very compact and it permits of the casing being made

very flat and comparatively light in weight. It also allows the knobs to be arranged in a row conveniently near each other. It is then very easy to pull down on any one or 5 on several of the knobs for the purpose of elevating one or more of the signal plates and it is also convenient to press upwardly simultaneously on one or all of the knobs to return the signals within the casing. It

10 will be understood that the rods are stiff or non-flexible so that the several signal plates may be operated in one direction by a pulling action on a rod and in the opposite direction by a pushing action thereon.

15 I have provided simple means for holding the signal plates in either position. The arbor 10 is here shown as square in cross section and for each of the signal plates 11, 12, 13, there is a bearing sleeve 25 having a 20 square central aperture 26 to fit the arbor 10 and be held from rotation on the latter. The signal plates turn in circular races 27 in the respective sleeves 25 so that the sleeves form bearings on the arbor for the signal 25 plates. Against the face of each signal plate there is arranged a spring disk 28, and one of the end plates may have a disk on both faces, as shown, though in one of these latter the snap device referred to hereinafter is pref-

30 erably omitted. When the signal plates and their spring disks are all assembled upon the arbor 10 ready for use the several disks are under compression and for this purpose I prefer to provide cotter pins 29 in the arbor 35 10 for holding the parts together with the disks under compression. The disks have square openings 30 corresponding with the shape of the arbor and therefore the disks do not turn on the arbor but remain stationary 40 relatively to the swinging motion of the signal plates. Each spring disk is provided with one or more projections, here shown, as stamped projecting studs 31. I have shown two such studs at opposite sides of the disks

45 and in the flattened rim portions 32 thereof. In the face of each signal plate there are provided depressions 33 into which the studs 31 snap when the signal plates are in either their raised or lowered position. There will 50 be two sets of depressions for the studs on an adjacent friction disk. One set is so arranged that the studs on an adjacent disk will enter therein when the signal is down, or inclosed in the casing and the other set 55 is so arranged that the same studs will enter therein when the signal plate is in the raised or signaling position. In addition to serving as resistance or friction members, the disks also serve to keep the signal plates 60 spaced apart on the arbor and they prevent side play of these plates on the arbor and thus prevent rattling.

The back of the casing has a flange 29 around three sides and through the open

end 7 there is inserted a mirror 31. When 65 the signal device is attached to the forward part and to one side of the automobile, as for instance to the windshield frame 8, the driver may observe vehicles approaching from the rear by looking into the mirror. 70

After the mirror has been inserted into place through the open end the detachable corner plates 34 are attached by screws 35 and these plates engage two of the corners of the mirror at the open end of the casing 75 and they hold it in place within its retaining flange.

I have shown a simple arrangement at the bottom to prevent the signal plates from shifting sidewise and rattling. Near the 80 bottom of the casing there is a cross pin 32, around which there is arranged a coiled spring 33 extending between the front and back walls. The position of the spring 33 is such that when the signal plates move down 85 to retracted position the edge of each one will enter between different coils of the spring. The lower ends of the signal plates can not then move laterally against each other as their lateral play is resisted by the 90 coils of the spring 33. This forms a most effective means for preventing rattling and one which is not likely to get out of order.

To operate the device one of the knobs 18, 21, or 24 is pulled downwardly and this will 95 raise one of the signal plates to a position at right angle to the casing as shown in Figs. 1 and 2. When the knob is first moved the recesses 33 on the signal plate adjacent the particular friction disk move away from the 100 studs 31 on this disk and the studs then press on the smooth surface of the signal plate. When the latter has about reached its raised or signaling position the other set of depressions come to register with the studs 31 and 105 the latter then snap into these latter depressions making a slight sound or click which will indicate that the signal has reached its final position. This snap action informs the operator when the signal plate has reached 110 its extreme upper position and also when it has been lowered into the casing and in addition, the studs 31 engaging in the depressions 33 more firmly hold the signal plates in one or the other of their extreme positions. 115 It requires a greater force to move one of the signal plates at the commencement of the movement in either direction, due to the fact that the studs 31 engage in the depressions 33 at the extreme positions.

Having thus described my invention, what I claim is:

1. In a signal device for automobiles a casing, swinging signal members adapted to be projected from and to be retracted in said casing; operating rods in said casing connected with the respective signal members and extending laterally therefrom relatively 125

different distances and thence downwardly and adapted to be operated from without the casing to swing the signal members.

2. In a signal device for automobiles a casing, signal members pivoted to swing whereby they may be projected from or retracted in said casing and means for holding

said signal members while in retracted position to prevent rattling and including a coiled spring disposed whereby the signal ¹⁰ members will enter between and be held in spaced relation by the coils of said spring.

Signed this 22nd day of June, 1917.

SAMUEL COHN.
